UNITED STATES PATENT OFFICE.

JOHN DUSZA, OF BROOKLYN, NEW YORK.

DEVICE FOR TRIMMING LINOTYPE-SLUGS.

1,361,030.

Specification of Letters Patent. Patented Dec. 7, 1920.

Application filed March 19, 1919. Serial No. 283,582.

To all whom it may concern:

Be it known that I, JOHN DUSZA, a citizen of the United States, residing in the borough of Brooklyn, of the city of New York, in the State of New York, have invented certain new and useful Improvements in Devices for Trimming Linotype-Slugs, of which the following is a specification, reference being had to the accompanying drawings, forming a part hereof.

Various attachments for trimming the slugs for linotype and printing machines have been devised and while many may be said to operate on somewhat the same principle there still remains a field for the improvement of such devices from both the manufacturers' and the users' standpoint. The present invention has for its object to provide a cutting device of the character referred to which is of simpler construction than heretofore, cheaper to manufacture and assemble and more accurate and durable in use.

In the drawings

Figure 1 is a view in front elevation of a trimming device.

Fig. 2 is a view in rear elevation of the same.

Fig. 3 is a view partly in section taken on the planes indicated by the line 3—3 of Fig. 1 and looking in the direction of the arrows.

Fig. 4 is a view, partly in section taken along the plane indicated by the line 4—4 of Fig. 1 and looking in the direction of the arrows.

Fig. 5 is a view in horizontal section taken on the plane indicated by the line 5—5 of Fig. 1 and looking in the direction of the arrows.

The attachment consists, generally speaking, of a relatively stationary plate *a* and a relatively adjustable knife slide *b* mounted in a frame *c* secured to the plate *a* by means of bolts *c'* and spacing studs *c''*, both passing through the lugs *c''* on the frame *c*. On the fixed plate *a* is mounted a relatively stationary knife *d* with which co-operates a relatively adjustable knife *e* between which knives the metal passes after being cast and is trimmed according to the size desired for the type point to be used. The invention relates particularly to the devices for securing the desired adjustment of the knife *e* on the frame *c*.

Referring particularly to Fig. 5 it will be seen that the knife slide *b* carries a threaded

stud *b'* the head of which is provided with a handle *b''* to permit quick manual operation for the purpose of backing the stud *b'* out of the knife slide *b*. The stud *b'* passes through a slot *c'* formed in a flange *c''* of the frame *c* overhanging the knife slide *b*. On the frame *c* there is mounted pivotally, as at *f*, a bell crank *f'*, one arm of which is slotted, as at *f''*, to engage the stud *b'* loosely. This forked end *f''* of the lever *f'* embraces the stud *b'* directly under the enlarged head *b''* by which, through manipulation of the handle *b''*, the head *b''* may be drawn into locking engagement with the lever *f'* to hold the knife slide *b* against movement. Since the position of the knife *e* depends upon the position of the knife slide *b*, it will be seen that suitable operating devices for determining the position of this knife slide in accordance with the type point required must be employed. These devices should be of simple construction from the manufacturers' standpoint and so hardened and interrelated that they will be at once durable and very accurate to give the precise trimming required for any particular adjustment. It is the primary object of this invention to improve these devices in the manner indicated.

In the frame *c* there is journaled a rotatable shaft *g* which is provided with a knurled head *g'* and a circular dial *g''* so graduated as to indicate for any given position of the dial the type point which may be obtained in the trimming. Toward the other end of this shaft *g* may be formed integral therewith a ring *g''* which may be hardened and machined up very accurately for functioning in the manner to be described. After the shaft *g* is inserted in the frame *c*, the knurled head *g'* may be secured thereto by a set screw *g''*, the proper positioning of the shaft bringing the hardened ring *g''* in proximity with the reverse face of the frame *c*. A carrier *i* may then be placed on the end of the shaft *g*. This carrier is recessed to fit over the ring *g''* and a fillet is formed for compensation for dust and oil etc. The carrier *i* is secured to the shaft *g* by means of a screw *h*. Mounted radially in the circular flange of the carrier *i* is a series of gage plugs *l*, each of a length to insure the trimming of type for a particular point as will be described. These gage plugs *l* are hardened and secured in the carrier *i* in such manner as to extend radially therefrom and

concentrically arranged about the axis of the shaft g . The inner ends of these gage plugs l rest against the periphery of the hardened ring g^3 which may be either cylindrical or polygonal in outline. Each of the plugs l having once been set with its end abutting against the hardened surface of the ring g^3 may be secured permanently in this position by means of a screw l' . The exposed ends of the gage plugs l are intended to be engaged by means of a hardened anvil m set on the inner face of the knife slide b and in such relation to the series of gage plugs l that for a given setting of the rotatable carrier i the anvil may be moved into engagement with the exposed end of a gage plug by moving the knife slide b . To insure accurate setting of the carrier i to give the precise point desired according to the gage plug l which determines the setting of the knife e , there is provided a locking stud n which the operator may pass through any one of a series of apertures g^5 formed about the dial g^2 and into a recess c^6 formed in the frame c . By removing the stud n the dial may be set in any position according to the point desired and the stud then passed through the particular aperture g^5 which is then in registry with the recess c^6 thereby affording a positive locking of the carrier i for that particular setting. By thus locking the carrier it is certain that the particular gage plug l then alined with the anvil m will receive the anvil m in its intended relation and fractional errors of setting, such as might occur with a spring retaining device for the carrier i , are eliminated.

In operation the knife slide b is released by backing out the stud b' and retracting the 40 knife slide from the carrier i by means of the bell crank f' . The carrier i with its protruding gage plugs l is then free to rotate. The locking stud n is withdrawn from the dial g and the carrier rotated until the dial 45 indicates that that gage plug l which will give the number of points of type desired is alined with the anvil m . The locking stud n is then replaced so as to maintain this alinement. The bell crank f' is then operated to bring the anvil m against the exposed end of the alined gage plug l whereupon the stud b' is screwed into the knife slide until the head b^3 acting on the lever f' locks the knife slide b against further movement. 50 This setting gives the proper clearance between the knives d and e for the type point desired.

Attention is invited particularly to the construction of the shaft g with the hardened ring g^3 integral therewith and to the relation of the carrier i to the shaft and the ring. This construction is not only of importance from the manufacturers' standpoint but permits the ring g^3 to be hardened 60 and receive the ends of the hardened gage

plugs l without danger of any wear between the parts or loss of accuracy in the setting. The plugs l may be hardened as well as the anvil m so that when the parts are once properly machined and set there is no opportunity for wear and consequent loss of accuracy. Further the radial disposition of the gage plugs l with relation to the shaft g and the carrier i is to be particularly noted as constituting an improvement over known cutting devices. 70 75

Another feature of construction consists of the improved back plate o disposed in such relation to the trimming knives d , e as to prevent the type from being thrown too far through the knives. This plate o is hingedly engaged with the knife slide b through lugs o' and is pressed forwardly against the lugs by means of a spring pressed plunger p carried in the knife slide b and backed up by a spiral spring p' . The function and action of the plate o on the slugs will be understood from known devices of somewhat similar character but different construction. 80 85 90

The appended claims are intended to cover those features of improvement which have been particularly emphasized herein, or their equivalents.

I claim as my invention:

1. In an attachment of a linotype machine for trimming slugs, a fixed knife, a movable knife, a series of gage plugs to permit the adjustment thereof, a rotatable carrier in which the plugs are mounted radially, a shaft on which the carrier is secured and a hardened ring formed integral with the shaft and disposed within the carrier to form a seat for the inner ends of the plugs. 95
2. In an attachment of a linotype machine for trimming slugs, a fixed knife, a movable knife, a rotatable carrier, a series of gage plugs mounted radially in the carrier to determine the adjustment between the knives, a frame on which the carrier is mounted, a dial carried with the carrier to indicate the adjustment, said frame and dial being provided with apertures, and a plug to enter said apertures when in registry to lock the carrier in position for the desired adjustment. 105 110 115
3. In an attachment of a linotype machine for trimming slugs, a fixed knife, a movable knife, a frame, a rotatable carrier, a series of gage plugs mounted in the carrier, a knife slide to which the movable knife is secured, an anvil on the knife slide to engage the end of an alined plug, an elbow lever mounted on the frame and engaging the knife slide operatively, and means to lock the knife 120 slide in adjusted position. 125
4. In an attachment of a linotype machine for trimming slugs, a fixed knife, a movable knife, a frame, a rotatable carrier, a series of gage plugs mounted in the carrier, a knife 130

slide to which the movable knife is secured, an anvil on the knife slide to engage the end of an alined plug, an elbow lever mounted on the frame and engaging the knife slide operatively, and a locking stud threaded into the knife slide and engaging the end of the elbow lever whereby the slide may be clamped in adjusted position.

5. In an attachment of a linotype machine for trimming slugs, a fixed knife, a movable

knife, a series of gage plugs to permit the adjustment thereof, a rotatable carrier in which the plugs are mounted radially and a hardened seat carried with the shaft and disposed within the carrier for engagement by 15 the inner ends of the plugs.

This specification signed this 14th day of March, A. D. 1919.

JOHN DUSZA.
